[57] ABSTRACT

A device adapted to temporarily hold multiple loops of the winding formed of a continuous strand of textile material in a proper relationship for cooperation with a sewing machine (or other joining apparatus) in a manner which will not obstruct the operation of the sewing machine for sewing a junction means along the multiple loops of continuous-strand textile material in a direction transverse to the adjacent multiple loops

thereof for facilitating the making of fringe. The device holds the multiple loops of the winding in the form of a flattened spiral or helix extending along the length of a flat winding core or longitudinal body portion and in a manner where an intervening portion of each loop extends across a longitudinal joining or sewing recess extending in a longitudinal direction from at least one longitudinal end of the winding core or longitudinal body portion to a location adjacent to the opposite end thereof, thus making it possible to wind a continuous strand of textile material into a flat spiral or helical winding extending any desired length (corresponding to the desired fringe length) along the winding core or longitudinal body portion and with laterally adjacent parts of the multiple loops of the winding extending across said longitudinal joining or sewing recess, which may then be placed in a cooperative position with respect to the upper and lower sewing elements of a sewing machine and relatively longitudinally moved so as to provide a longitudinal sewing junction in the length direction of the flat helical or spiral winding of the multiple loops of the textile material so that they will be firmly joined along the length of the winding and laterally with respect to the direction of each of the multiple loops thereof at a desired transverse location between opposite looped ends of the multiple loops, after which the continuous winding having such a sewing junction extending along the length of the winding may be slidably removed from the winding core of the longitudinal body portion and used "as is" or may have the loop ends cut, if desired, whereby to produce a desired length and width of fringe in a simple and easy manner.

FRINGE-MAKING DEVICE

BACKGROUND OF THE INVENTION

The field of the invention is generally that of fringe-making and sewing devices and apparatus and, in particular, apparatus and devices of a relatively simple nature intended for use in making fringe. Most such prior-art fringe-making devices or apparatus are of relatively complex types intended primarily for large-scale industrial usage. No relatively simple prior art apparatus intended primarily for use by an individual, such as an individual woman sewing at home, or the like, is known to exist, and it is precisely this desirable objective which is achieved in and through the use of the novel, extremely simple, fringe-making device of the present invention.

SUMMARY OF THE INVENTION

Generally speaking, the fringe-making device of the present invention comprises a textile strand winding core taking the form of a longitudinal body portion (usually of substantially flat planar material) terminating in longitudinally spaced opposite ends and with said longitudinal body portion having opposed transversely spaced side edges (which are usually in substantially parallel relationship to each other) extending substantially between said longitudinally spaced ends. Thus, in the preferred form just referred to, the effective winding core is of substantially flat, rectangular configuration, with the transversely spaced side edges thereof being spaced apart and with the longitudinal ends thereof being spaced apart by an intervening or intermediate part of the longitudinal body portion and with the whole of said effective winding core functioning comprising a textile-strand-winding receiver cooperable for receiving and having wound therearound in a flat spiral or helix, a continuous length or strand of textile material, with the winding extending axially or longitudinally a desired length along the longitudinal direction of the longitudinal body between the opposite longitudinally spaced ends thereof. The longitudinal body portion has a longitudinal textile strand joining or sewing recess in a desired transverse location with respect to the transversely spaced side edges thereof and extending in a longitudinal direction from at least one of said longitudinal ends of the body portion along a substantial portion of the length of the longitudinal body portion (usually to a position closely adjacent to the opposite end of the longitudinal body portion). The textile strand joining or sewing recess has an entry opening at one end of the longitudinal body portion usually provided with controllably openable and closable entry gate or keeper means which is controllably removable to allow textile strand junction means formed along the length of the recess in and across corresponding portions of a plurality of loops of a continuous winding of a length or strand of textile material to be removed through said entry opening when said entry gate or keeper means is controllably removed or opened. The textile strand joining or sewing recess mentioned above is of a width such as to be cooperable with the upper and lower sewing elements of a sewing machine whereby to allow the upper and lower sewing elements of a sewing machine to be moved longitudinally along the length of said recess while being operated so as to join (by sewing) said adjacent loops of

such a continuous strand of textile material carried in the form of a spiral or helical winding around and along the length of said core means. In one preferred form of the invention, the longitudinal body portion is provided adjacent to a first one of said ends thereof with a first textile material strand engaging and fastening means cooperable with a first effective end portion of a strand of textile material for firm fastening engagement with respect thereto at one end of a winding of said strand of textile material which is to be formed around and along the length of said longitudinal body portion comprising said effective core means. In a preferred form of the invention, the longitudinal body portion is provided adjacent to a second one of said ends thereof with a second textile material strand engaging and fastening means cooperable with a second effective end portion of a strand of textile material at the opposite end of such an intervening winding formed of a continuous length of such textile strand material wound around and extending along a substantial portion of the length of said longitudinal body portion between said first and second textile material strand engaging and fastening means. In a preferred form, the longitudinal body portion is made of integral, flat, thin-sheet construction and, in one exemplary embodiment thereof, may be integrally formed of flat, thin-sheet metallic material, although not specifically so limited in all forms thereof.

Also, in one form of the invention, the longitudinal body portion is provided with length-adjustment means which is cooperable for controllable adjustment in a manner correspondingly controllably adjusting the overall length of the longitudinal body portion (and the intervening joining or sewing recess means) between the longitudinally spaced opposite ends thereof.

Also, in one preferred form of the invention, the longitudinal body portion is provided with width-adjustment means which is cooperable for controllable adjustment in a manner correspondingly controllably adjusting the effective width of said longitudinal body portion between said transversely spaced side edges of said textile strand winding core means.

OBJECTS OF THE INVENTION

With the above points in mind, it is an object of the present invention to provide a novel device for facilitating the making of fringe which is of the character referred to herein, generically and/or specifically, which may include any or all of the features referred to herein, either individually or in combination, and which is of extremely simple, inexpensive, easy-to-use, and easy-to-manufacture construction suitable for ready mass manufacture and distribution of the device at an extremely low cost per unit, both as to initial capital cost (including production set-up cost, etc.) and as to the subsequent per-unit manufacturing cost, whereby to be conductive to widespread production, distribution, sale, and use of the invention for the purposes outlined herein or for any substantially equivalent or similar purposes.

Further objects are implicit in the detailed description which follows hereinafter (which is to be considered as exemplary of, but not specifically limiting, the present invention), and said objects will be apparent to persons skilled in the art after a careful study of the detailed description which follows.

For the purpose of clarifying the nature of the present invention, several exemplary embodiments of the invention are illustrated in the hereinbelow-described figures of the accompanying drawings and are described in detail hereinafter.

BRIEF DESCRIPTION OF THE DRAWINGS

FIG. 1 is a reduced-size perspective view showing one exemplary form of the invention in a pre-fringe-making-use condition.

FIG. 1A is a fragmentary, partially broken-away, sectional view taken substantially along the plane and in the direction indicated by the arrows 1A—1A of FIG. 1.

FIG. 2 is a view generally similar to FIG. 1, but illustrates the device after a desired length of textile material strand has been fastened thereto at one end, has been wound therearound (with the winding being shown in incomplete, interrupted form for reasons of drawing clarity), and after the opposite end of said strand of textile material has been fastened thereto — all for fringe-making purposes. This view in effect may be said to comprise the first step in making fringe with the device.

FIG. 3 is a view of the device of FIG. 2 in an oblique orientation and shows the device carrying a textile strand winding thereon and placed in a cooperative relationship with respect to an-only-partially-shown sewing means, which usually includes upper and lower sewing elements (only the upper one of which is fragmentarily shown and is to be construed as being representative of the entire sewing means) of a sewing machine (which is broken away except for the upper element of the sewing means fragmentarily shown for representative purposes). The partial and fragmentary showing of the sewing means and the complete breaking away and removal of the sewing machine are done for space-saving reasons and for reasons of drawing clarity, particularly in view of the fact that such apparatus is well-known in the art and does not touch upon the real inventive concept of the present invention. The partially and fragmentarily shown sewing means of such a sewing machine is illustrated in this figure in the act of forming a longitudinal junction means (by sewing the adjacent loops of the winding of the strand of textile material) along the textile strand joining or sewing longitudinal recess carried by the device of the present invention to make this possible. FIG. 3 may be said to comprise the next step in the fringe-making operation immediately following the FIG. 2 step thereof.

FIG. 4 is a view illustrating the next sequential step in the fringe-making operation after completion of the sewing operation of FIG. 3, comprising the removal or opening of the controllably openable and closable entry gate or keeper means normally effectively closing the entry opening at the right end of the longitudinal textile strand joining or sewing recess, which, thus, allows the longitudinal junction means formed by the sewing shown in FIGS. 3 and 4 to be removed along with the rest of the complete winding (shown in incomplete interrupted form for drawing clarity) from the device of the present invention in the manner shown partially completed in this figure.

FIG. 5 illustrates the removed longitudinal winding of the continuous strand of textile material, which is joined between opposite ends of the winding by the junction means provided by the sewing shown in suc-

cessive degrees of completion in FIGS. 3 and 4. Also, this view illustrates the cutting of the opposite side edges of the loops of the winding by suitable cutting means indicated diagrammatically in the form of two spaced cutting edges, or cut lines only, whereby to produce the cut fringe of FIG. 6.

FIG. 6 merely illustrates the completed fringe produced by the sequence of operations shown in FIGS. 2 through 5.

10 FIG. 7 is a view of a somewhat simplified and diagrammatic nature illustrating the longitudinal body portion as being provided with length-adjustment means for adjusting the overall length thereof and is merely representative of one exemplary form thereof.

FIG. 8 is a sectional view taken substantially along the plane and in the direction indicated by the arrows 8-8 of FIG. 7.

FIG. 9 is a view of a somewhat simplified and diagrammatic nature illustrating the longitudinal body portion as being provided with width-adjustment means for adjusting the overall width thereof and is merely representative of one exemplary form thereof.

FIG. 10 is a fragmentary, partially broken-away, greatly enlarged view of the portion of the device of FIG. 9 lying within the phantom-line circle indicated by the arrow 10 of FIG. 9.

DESCRIPTION OF THE PREFERRED EMBODIMENTS

The exemplary first form of the invention comprises a textile strand winding core means, indicated generally at 20 and having a longitudinal body portion 22 terminating in longitudinally spaced opposite ends 24 and 26, and all of which together comprise said textile strand winding core means indicated generally at 20. In the example illustrated, the entire core means 20 and the longitudinal body portion 22 thereof are of substantially flat planar construction having a substantially rectangular shape defined by a pair of transversely spaced side edges 28 and 30 which, in the example illustrated, are substantially parallel to each other and which extend substantially between the longitudinally spaced ends 24 and 26.

45 The longitudinal body portion 22 has a longitudinal textile strand joining or sewing recess, indicated generally at 32, extending in a longitudinal direction from at least one end (in the example illustrated, the right end 24, although not specifically so limited) along a substantial part of the length of the longitudinal body portion 22 toward and closely adjacent to an inner terminus 34 which is adjacent to the opposite longitudinal end 26.

55 It should be noted that the longitudinal textile strand joining and sewing recess 32 lies at a predetermined transversely spaced location between and substantially parallel to the two transversely spaced side edges 28 and 30 of the longitudinal body portion and that it is defined by and between opposed recess edges 36 and 38 which, at one end, extend only to the inner recess terminus 34, but at the other end thereof (the right end 24 of the longitudinal body portion 22 in the example illustrated) extend to, and define, an entry opening (best shown at 40 in FIG. 4) which is normally provided with a controllably openable and closable entry gate or keeper 42, which is controllably openable or removable in the manner shown in FIG. 4 whenever the

normally closed entry opening 40 is to be temporarily opened for the purpose of allowing the removal of the longitudinal sewing junction 44 (which will be described in greater detail hereinafter) of a complete textile strand winding, such as is indicated generally at 46 and which will be described in greater detail hereinafter, from the textile strand winding core means 20 in a manner such as is clearly shown in FIG. 4.

It should be noted that, in the example illustrated, the entry gate or keeper 42 has opposed slots, as best shown at 48 and 50 in FIG. 1A, arranged for slidable cooperation with the recess edges 36 and 38 at the right ends thereof where they define the previously mentioned entry opening 40 so that said entry gate or keeper 42 can be slidably engaged with said recess edges 36 and 38 and slidably moved from the open position shown in FIG. 4 into the closed position shown in solid lines in FIGS. 1, 1A, 2, and 3 and shown in broken lines in FIG. 4, and vice versa, whenever desired.

It should be noted that the width of the recess 32 is such as to provide for ready cooperation with the sewing means, indicated fragmentarily and diagrammatically in broken-away form at 52 in FIG. 3 of a conventional sewing machine, so that relative movement of the device and said sewing means 52 along the length of the joining or sewing recess 32 can occur when it is desired to join, by sewing, a series of adjacent multiple loops 54 of the previously mentioned continuous textile strand winding 46 formed of a continuous length or strand of textile material. This is for the fringe-making purposes of the present invention, as will become more apparent hereinafter.

The longitudinal body portion 22 is normally provided with a first fastening means for fastening a first end, or portion, of a strand of textile material prior to winding it around the central part of the longitudinal body portion 22 so as to form the flat spiral or helical winding or textile strand material, as indicated at 46, along the length of the longitudinal body portion. Also, the longitudinal body portion is normally provided with a second longitudinally spaced fastening means for fastening a second end, or spaced portion, of the strand of textile material so that it may be fastened after the winding operation, producing the winding 46, has been completed.

In the first example illustrated, the two above-mentioned fastening means comprise a first effective textile material strand engaging and fastening means, taking the form of notch means 56, into which a portion of a continuous strand or length of textile material can be fastened or locked when the device is in the general pre-winding condition shown in FIG. 1. Then the length of textile strand material can be wound around the central part of the longitudinal body portion 22 so as to tightly engage the transversely spaced side edges 28 and 30 and so as to lie closely across the flat intermediate part 58 of the longitudinal body portion 22 on both sides thereof in a plurality of closely adjacent multiple loops 54 of a continuous flat spiral or helix comprising the previously mentioned winding 46.

As the winding operation is performed, the adjacent loops 54 can be manually slidably moved toward the left end so as to be packed very tightly together if desired, and the winding operation can continue for as long as desired and as long as permitted by the available length of the longitudinal body portion 22. When

the winding 46 reaches a desired length, the free portion of the continuous strand of textile material is then fastened in the second above-mentioned textile material strand engaging and fastening means which, in the example illustrated, is shown as another V-shaped notch means as indicated at 60. The portion of the strand of textile material engaged in the notch means 60 can be firmly fastened and locked therein by force inwardly. This second step in the use of the fringe-making device of the present invention which results in the production of the winding just described is clearly illustrated in FIG. 2.

Then the entire device carrying the textile strand winding 46 is moved into the relationship shown in FIG. 3 so that the cooperable sewing means 52 of a sewing machine (not shown), or any other equivalent sewing or joining means, can be caused to form a junction means, such as that shown at 44, along the length of the winding 46 so that the adjacent loops 54 of the winding will be firmly fastened to each other along the entire junction means 44. This third step in the use of the device of the present invention for fringe-making purposes is clearly shown in FIG. 3.

Then the entire device is removed from the sewing means 52 and the entry gate or keeper 42 is slidably removed from the normally closed entry opening 40 in the manner best shown in FIG. 4. As soon as the fastened ends of the textile strand are removed from the fastening means 56 and 60 or as soon as the free ends thereof beyond the sewing junction means 44 are cut, the entire winding means 46 can be readily slidably moved rightwardly relative to the longitudinal body portion and completely off of the device in the manner shown in the act of occurrence and partial completion in FIG. 4. This is made possible by reason of the entry opening 40 and the openable or removable entry gate or keeper 42.

The primary reason that the entry gate or keeper 42 is present at all times except when the winding means 46, having the longitudinal junction means 44 along the length thereof and lying within the recess 32, is to be removed, is to provide strength and support to the right end 24 of the longitudinal body portion 22. In certain forms of the device where the longitudinal body portion is made of sufficiently stiff or strong material, the entry gate or keeper 42 can be eliminated. However, generally speaking, it will be found that this requires higher strength or thicker and stronger and, consequently, heavier and more expensive materials and construction for the entire device than is the case when the entry gate or keeper 42 is used to provide strength and support for the right end of the device during normal usage. The type of construction illustrated makes it possible to make the entire device of relatively thin, lightweight, inexpensive material and generally this is thought to be a sufficient advantage to warrant the use of the entry gate or keeper means 42 in a preferred form of the invention.

After the winding 46 is removed in the manner shown in FIG. 4, it may then have the opposite loop ends of the multiple loops 54 of the continuous winding 46 cut along the two cut-line locations or knife-edge locations indicated diagrammatically by the broken lines 62 and 64 in FIG. 5. Any suitable cutting means may be employed for this purpose, and details thereof are not shown since knives, scissors, or any other type of cutting means suitable for this purpose are well-known in

the art and do not touch upon the real inventive concept of the present invention. After cutting the loop ends along the two cut-line locations indicated at 62 and 64 in FIG. 5, the multi-strand fringe means, generally designated by the reference numeral 66 in FIG. 6, will have been produced in and through the use of the relatively simple device of the present invention and the sequence of steps shown in FIGS. 1 through 5 inclusive.

It should be noted, in connection with the textile strand material employed in making the original winding 46, which ultimately produces the fringe means 66 of FIG. 6, that virtually any kind of textile strand may be employed. It may comprise yarn, cord, string, or other textile strand material of any desired degree of thickness and having any desired type of characteristics. Furthermore, it should be noted that the fringe may be made of any desired length, as permitted by the length of the longitudinal body portion, which may be supplied in a series of different sizes or lengths or which may be supplied in a length-adjustable form as illustrated in one representative form in FIGS. 7 and 8, which will be referred to hereinafter. Furthermore, the fringe may be made of any effective width (width, meaning the direction between the opposite cut loop ends or cut lines such as shown at 62 and 64 in FIG. 5) by providing the device in various different width sizes or by providing it in a width-adjustable form, one representative version of which is illustrated in FIGS. 9 and 10, as will be briefly referred to hereinafter.

With reference to the length-adjustable representative form shown in FIGS. 7 and 8, it should be noted that reference numerals similar to those used for designating parts of the first form of the invention, but followed by the letter "a," however, are used to designate functionally equivalent or similar parts of this length-adjustable modification. It will be noted that the major change in this length-adjustable modification is the fact that the longitudinal body means, indicated generally at 22a, is provided with length-adjustment means, indicated generally at 68, which is cooperable for controllably adjusting the overall length of the longitudinal body portion 22a between the opposite longitudinally spaced ends 24a and 26a thereof while correspondingly also adjusting the length of the longitudinal joining or sewing recess 32a. The telescopic and effectively frictional engagement of the two cooperating mating parts of the length-adjustment means 68 are clearly shown in FIGS. 7 and 8 in a representative form only — it being understood that they may be modified substantially within the broad scope of the present invention by the provision of various other type of length-adjustment means and various other types of locking or holding means for holding the length-adjusted portions in any of a variety of different selected length-adjusted relationships.

FIGS. 9 and 10 merely illustrate an arrangement similar in principle to the just-described length-adjustable modification of FIGS. 7 and 8, but, in this case, comprising a width-adjustable construction having width-adjustment means, indicated generally at 68b, and comprising telescopically and frictionally slidably matingly engaged parts quite similar in principle to those shown at 68 in FIGS. 7 and 8, but, in this case, being transversely rather than longitudinally directed. Otherwise, this modification is very similar to the FIGS. 7 and

8 modification, and parts which are functionally equivalent (although, in the case of the width-adjustment means 68b, being transversely rather than longitudinally directed) are designated by the same reference numerals as used in FIGS. 7 and 8, followed by the letter "b," however, in the width-adjustment modification of FIGS. 9 and 10. It is believed that any further description of the width-adjustable modification would be redundant and is unneeded in view of the full description of the first form of the invention illustrated in FIGS. 1-4 inclusive and of the first adjustable modification illustrated in FIGS. 7 and 8.

In one preferred form, the entire winding core, including the longitudinal body portion and the opposite ends thereof may be formed of very simple, flat, planar, thin-sheet, stamped, metal construction which is extremely simple and inexpensive to manufacture. In this form, the entry gate or keeper means may be made of stamped, cast, or molded construction, either of metal or of plastic resin and, in the example illustrated, is shown as being made of molded plastic resin, although not specifically so limited. It should also be noted that the entire device can be formed very readily from plastic material and, because of its thin-sheet construction, can be made from plastic sheet stock rather than by more expensive molding techniques if desired.

It should be understood that the figures and the specific description thereof set forth in this application are for the purpose of illustrating the present invention and are not to be construed as limiting the present invention to the precise and detailed specific structure shown in the figures and specifically described hereinbefore. Rather, the real invention is intended to include substantially equivalent constructions embodying the basic teachings and inventive concept of the present invention.

What is claimed is:

1. A device adapted to hold multiple loops of a continuous strand of textile material in the form of a winding for cooperation with an auxiliary joining apparatus for facilitating the making of fringe, comprising: a textile strand winding core means having a longitudinal body portion terminating in longitudinally spaced opposite ends and with said longitudinal body portion having opposed transversely spaced side edges extending substantially between said longitudinally spaced ends, said body portion including said transversely spaced side edges thereof, and an intermediate part of said body portion between said transversely spaced side edges thereof, comprising a textile strand winding receiver cooperable for receiving and having wound therearound, in the form of a flattened helical winding, a continuous length or strand of textile material, and with said winding extending a desired length in a longitudinal direction along the length of said body portion between said opposite longitudinally spaced ends, said body portion having a longitudinal textile strand joining recess extending in a longitudinal direction from at least one of said ends of said body portion along the length of said body portion at a predetermined transversely spaced location between said transversely spaced side edges of said body portion to a recess terminus adjacent to the opposite end of said body portion, said opposite end of said body portion being rigid whereby to effectively rigidify and maintain the relative positions of side parts of said body portion on each side of said textile strand joining recess at said recess terminus.

nus; said textile strand joining recess having an entry opening at one of said ends of said body portion to allow removal of textile strand junction means previously formed longitudinally along the length of said recess in and across corresponding portions of a plurality of loops of a continuous strand of textile material previously transversely wound around said body portion comprising said textile strand winding receiver and extending transversely across said longitudinal recess; said entry opening defined by said one end of said longitudinal body portion at said corresponding end of said textile strand joining recess being of substantially narrower width in a transverse direction than the width of said end of said longitudinal body portion and being provided with a completely physically separate entry-opening-rigidifying entry gate and keeper means, which is similarly transversely of substantially narrower width in a transverse dimension than the width of said end of said longitudinal body portion and of a very slightly narrower width than the width of the corresponding entry opening and which is controllably insertible to a predetermined degree into said entry opening in firm positive edge tongue-in-groove rigidifying engagement with inwardly directed side edges of said longitudinal body portion on each side of and defining said entry opening in a manner positively and effectively forming a temporary end bridge across and entirely between said side edges of said longitudinal body portion defining said entry opening and positively rigidifying same in a manner producing great transverse rigidity across said entry opening and to the corresponding entire end of said longitudinal body portion having said narrower entry opening defined therein, and with said entry-opening-rigidifying entry gate and keeper means being controllably slidably temporarily completely removable from said tongue-in-groove rigidifying engagement with said immediately outwardly adjacent side edges of said longitudinal body portion defining said entry opening to allow said removal from the previously closed longitudinal joining recess of said textile strand junction means previously formed longitudinally along the length of said recess in and across corresponding portions of a plurality of loops of a continuous strand of textile material previously transversely wound around said body portion comprising said textile strand winding receiver and extending transversely

across said longitudinal recess.

2. A device as defined in claim 1, wherein said longitudinal recess is of a width such as to be cooperable with sewing means of auxiliary sewing apparatus to allow such sewing means to be relatively moved longitudinally along the length of said recess while being operated so as to join, by sewing, such corresponding portions of adjacent loops of such a winding of a continuous strand of textile material carried in wound-around form by said body portion comprising said textile strand winding receiver.

3. A device as defined in claim 2, wherein one of said side edges of said body portion is provided adjacent a first one of said ends thereof with first textile strand engaging and fastening means cooperable with a first effective end portion of a strand of textile material for firm fastening engagement with respect thereto at one end of a winding of said textile strand to be formed around said longitudinal body portion along the length thereof.

4. A device as defined in claim 3, wherein one of said side edges of said body portion is provided adjacent a second one of said ends thereof with a second textile strand engaging and fastening means cooperable with a second effective end portion of a strand of textile material at the opposite end of such an intervening winding of a continuous length of such a textile strand around an intervening intermediate part of said body portion between said first and second textile strand engaging and fastening means.

5. A device as defined in claim 4, wherein said longitudinal body portion is of integral flat thin-sheet construction.

6. A device as defined in claim 1, including length adjustment means cooperable for controllable adjustment in a manner correspondingly controllably adjusting the overall length of said longitudinal body portion between said longitudinally spaced opposite ends thereof.

7. A device as defined in claim 1, including width adjustment means cooperable for controllable adjustment in a manner correspondingly adjusting the effective width of said longitudinal body portion between said transversely spaced side edges of said textile strand winding core means.
